UNITED STATES PATENT OFFICE.

FRANK HERRON, OF LAS CRUCES, NEW MEXICO.

AUTOMATIC TIME-CONTROLLED DRAFT APPARATUS.

Application filed August 29, 1921. Serial No. 496,363.

To all whom it may concern:

Be it known that I, FRANK HERRON, a citizen of the United States, residing at Las Cruces, in the county of Dona Ana and

State of New Mexico, have invented certain new and useful Improvements in Automatic Time-Controlled Draft Apparatus; and I hereby declare that the following is a full, clear, and exact description thereof, refer-

ence being had to the accompanying drawings, which form part of this specification.

This invention is a novel time controlled device for opening the drafts on furnaces at a predetermined time. Various devices for such purpose have already been patented, but as stated the present invention provides a very simple, inexpensive and reliable device; and its object is to provide a very simple device which can be easily attached 20 to a furnace by ordinary house owners, and which will be efficient in operation and very inexpensive to purchase or install.

The invention is designed to enable house-holders to open the draft of the furnace at any desired hour in the morning, being particularly intended for use in residences where furnaces are employed which are banked by night and cool down during the sleeping hours, and it is desired to have the draft 20 turned on at such an hour in the morning as will insure that the house is properly heated when the occupants arise. I will explain the invention with reference to the accompanying drawings which illustrate one 35 practical embodiment thereof and will enable others to adapt and use the same; and in the claims I have summarized the novel features of the invention for which protection is desired.

40 In the drawings:

Fig. 1 is a diagrammatic view illustrating the arrangement of the time device and the connection thereof with an ordinary house heating furnace.

45 Fig. 2 is an enlarged view showing the time controlled operating mechanism.

Fig. 3 is a transverse detail sectional view of such mechanism on line 3—3 Fig. 2.

50 The furnace F may be a hot water, steam or hot air furnace of any suitable kind and is provided with a draft door, shutter or valve V of the usual kind, which is closed when the furnace is banked and may be opened when it is desired to give the furnace 55 a draft to heat it rapidly. As shown this valve V may be connected to one end of

a cord or chain R which cord may be led up over pulleys P so that the other end of the cord may be pulled downward thereby lifting the valve when it is desired to raise 60 or open it. Thus far the parts are old. In the present invention I preferably use as a weight a clock mechanism, such as an ordinary alarm clock C, which may be suspended from the end of the cord or chain R and serve 65 as a weight to hold the valve V raised. This clock mechanism, while of ordinary construction, is provided with a time controlled gripper whereby it may be suspended from a hanger block 1 which may be suspended 70 from or adjacent the last pulley support P. In the example shown this hanger 1 is wedge shaped, being smallest at its upper end, and is adapted to be engaged by the gripper connected to the clock as shown in 75 Fig. 2. This gripper preferably comprises two opposite members which are pivotally connected together and which have jaws 2 and 3 on their upper ends and are pivoted together at 3^a. Below the pivot 3^a the member 3 has a short arm 3^b and the member 2 has a longer arm 2^b. The lower end of the arm 3^b is pivotally connected at 3^c to the upper end of a bar 4; and the lower end of the arm 2^b is pivotally connected at 2^c to the lower 80 end of the bar 4. The bar 4 is pivoted at 4^a to the frame K of the clock mechanism inside the clock C and may project through a slot in the clock casing. The bar 4 has an arm 4^b projecting therefrom practically 85 at right angles thereto; and the end of this arm 4^b has a projecting tooth 4^c which is adapted to be engaged with a detent 5 on the inner end of the spring S which is ordinarily 90 used in this type of clock to control the alarm mechanism. The clock mechanism is not a feature of the invention and is merely conventionally indicated in the drawings, the particular clock mechanism used being immaterial; but in the particular mechanism 95 indicated is shown as "The American" alarm clock, made by the West Alarm Clock Co. This clock has a spring S which normally presses outwardly a gear T which forms a part of the alarm setting mechanism and is loosely mounted on the setting shaft G, said gear having a notch in its outer face. This setting shaft G has a disk J connected thereto adjacent gear T, this disk J having a pin j which is adapted to engage the notch 100 t on the gear T. The gear T rotates with the hour hand of the clock and when the

105

110

usual indicator *g* is set to the proper hour (as in setting the ordinary alarm) the pin *j* rides out of notch *t* and in so doing forces gear *T* back out of the way against the tension of the spring *S* and the gear is held back until in the course of the revolution of the gear *T*, the pin *j* again registers with the notch *t*. Then the spring *S* moves gear *T* forward and in so doing would, in the ordinary clock, release the alarm. In the present invention instead of releasing the alarm this movement of the spring *S* disengages the detent 5 from the arm 4^b.

When the arm 4^b is engaged with the detent 5 as indicated in full lines in Fig. 2, the jaws 2, 3 are closed. When the detent 5 disengages the arm 4^b the jaws would open.

In using the device the clock, as stated is attached to one end of the chain *R* and the owner sets the "alarm" to the hour at which he wishes the draft to be opened. He then raises the clock until the jaws 2 and 3 embrace the tapered hanger block 1. He then closes the jaws upon the block, as in Fig. 2, and in so doing the arm 4^b is engaged under the detent 5 thus holding the jaws locked as indicated in Fig. 2, and the clock will then be suspended by said jaws from the hanger block 1, and the valve *V* will remain closed.

At the hour for which the alarm is set the pin *j* enters the notch *t* and spring *S* thereupon disengages detent 5 from arm 4^b. The weight of the clock and tapered sides of the hanger 1 cause the jaws 2 and 3 to open up and disengage the hanger and the weight of the clock is then transferred to the chain *R* and through it to the valve *V* opening the latter as indicated in dotted lines in Fig. 1, thus turning on the draft at the hour desired. The weight of the clock would ordinarily be sufficient to open a light valve *V* but if the clock is too light the weight of the clock could be supplemented by attaching any kind of a suitable weight to the clock or to the cord *R* in such manner that the weight would be suspended by the clock when the jaws 2 and 3 are engaged with the hanger and would supplement the weight of the clock in pulling down the chain and opening up the valve when the jaws 2 and 3 are released.

What I claim is:

1. In mechanism of the character specified, a time mechanism; a gripper comprising pivotally connected members having opposed jaws above their pivot, one member having a short arm and the other member having a long arm below their pivot; a bar pivoted to the time mechanism having its opposite ends respectively connected with the long and the short arms of the gripper members, an arm projecting from said bar adapted to engage a detent on the alarm spring of said time mechanism to hold the

jaws in locked position; whereby when said alarm spring is actuated, said arm will be disengaged from said detent allowing the jaws to open, substantially as described.

2. In mechanism of the character specified, 70 a time mechanism, a gripper comprising pivotally connected members having opposed jaws above their pivot, one member having a short arm and the other member having a long arm below their pivot; a bar 75 pivoted to the time mechanism having its opposite ends respectively connected with the long and the short arms of the gripper members, an arm projecting from said bar and having a tooth adapted to engage a 80 detent on the alarm spring of said time mechanism to hold the jaws in locked position; whereby when said alarm spring is actuated, the said tooth and detent will be disengaged and the jaws will be opened, 85 substantially as described.

3. In combination with a clock mechanism, 90 a gripper comprising pivotally connected members having opposed jaws above their pivot, one member having a short arm and the other member having a long arm below their pivot; a bar pivoted to the time mechanism having its opposite ends respectively connected with the long and the short arms of the gripper members, an arm projecting 95 from said bar and having a tooth adapted to engage a detent on the alarm spring of said time mechanism to hold the jaws in locked position, means controlled by the clock mechanism for releasing the gripper at 100 a predetermined hour; and a hanger adapted to be engaged by the gripper to suspend the clock mechanism.

4. In combination with a clock mechanism, 105 a hanger; a gripper connected with the clock mechanism to engage the hanger; said gripper comprising pivotally connected members having opposed jaws above their pivot, one member having a short arm, and the other member having a long arm 110 below the pivot; a bar pivoted to the clock mechanism and having its opposite ends respectively connected with the long and the short arms of the gripper members; an arm projecting from said bar and having a tooth 115 on the outer end thereof engaging a detent on the alarm spring of said clock mechanism to hold the jaws in locked position; and means controlled by the alarm time mechanism of the clock to disengage said tooth and detent at a predetermined hour thereby permitting the gripper jaws to release the hanger at the time it is desired to have the valve open, and allow the clock to drop.

5. In combination with a member to be operated, a clock mechanism, a hanger; a gripper connected with the clock mechanism to engage the hanger, said gripper comprising pivotally connected members 120 members, an arm projecting from said bar adapted to engage a detent on the alarm spring of said time mechanism to hold the

having opposed jaws above their pivot, one member having a short arm and the other member having a long arm below the pivot; a bar pivoted to the clock mechanism and having its opposite respective ends connected with the long and the short arms of the gripper members; an arm from said bar and having a tooth on the outer end thereof engaging a detent on the alarm spring of said

clock mechanism to hold the jaws in locked 10 position; and means controlled by the time mechanism of the clock for permitting the gripper to release the hanger at the time it is desired to have the member operated and thus allow the clock to drop.

In testimony that I claim the foregoing as my own, I affix my signature.

FRANK HERRON.
